(57) **CLAIM**

The ornamental design for an electrical cam lock with mechanical override, as shown and described.

DESCRIPTION

The patent file contains at least one drawing executed in color. Copies of this patent with color drawing(s) will be provided by the Patent and Trademark Office upon request and payment of the necessary fee.

FIG. 1 is a perspective view thereof;

FIG. 2 is a right side view thereof;

FIG. 3 is a left side view thereof;

FIG. 4 is back view thereof;

FIG. 5 is a front view thereof;

FIG. 6 is a top view thereof; and,

FIG. 7 is a bottom view thereof.

The broken lines in the figures depict portions of the electrical cam lock with mechanical override that form no part of the claimed design.
